COOKING RANGE

Jack G. Elmore, Effingham, Ill., assignor to Borg-Warner Corporation, Chicago, Ill., a corporation of Illinois

Application May 27, 1955, Serial No. 36,255

Term of patent 14 years

(Cl. D81—4)

*Fig. 2**Fig. 3*Fig. 1 is a perspective view of a cooking range embodying my new design showing the cooking range with all appurtenances in the closed position;

Fig. 2 is a perspective view of the cooking range of Fig. 1 showing the cooking range with the upper compartment in the open position and the cooking top and the lower compartment in the extended position; and

Fig. 3 is a perspective view of the cooking range of Fig. 1 showing the cooking range with the intermediate compartment in the extended position.

I claim:

The ornamental design for a cooking range, as shown and described.
